[57] ABSTRACT

A zero suppression circuit for a display of an electronic calculator or the like employs a register which includes n flip-flops for storing a decimal point signal and signals representing whether the digits of respective places are any of the digits 1 to 9, and a detector circuit which includes n OR gates, the i -th gate of the detector circuit being supplied with the output signals of the first to i -th flip-flops of the register. An output "0" of the i -th OR gate signifies that neither a digit from 1 to 9 nor a decimal point exists in and below the i -th place, so the digit 0 in the i -th place is unnecessary. Through such a judgement, the unnecessary zeros below the decimal point are prevented from being indicated in the display. When further detector circuits are provided, unnecessary zeros in the upper places can also be prevented from being indicated.

FIG. 3

ZERO SUPPRESSION CIRCUIT

BACKGROUND OF THE INVENTION

1. Field of the Invention

The present invention relates to the indicator circuit of an electronic calculator or the like and, more particularly, to a zero suppression circuit for preventing unnecessary zeros below a decimal point from being indicated.

2. Description of the Prior Art

In conventional electronic desk calculators and the like, all the places of an indicating device are brought to the zero indication after the closure of the power supply switch. Subsequently, when the first or second operand is set or when a calculated result is requested, all the places except those necessary for the indication are indicated as zeros. For example, where a four-figure number 1234 is set, an expression 001234.00 is given by the indicating device.

With such an indicating system, the unnecessary zeros are indicated in the places above and below those required for the indication. For this reason, the indication is difficult to read, and misreading may become a problem.

Where, with the miniaturization of the electronic desk calculator, a battery is employed as the power supply, the power consumption of the calculator must be made low in order to lengthen the life of the power supply. Since the indicating portion exploits electro-optic conversion, the power consumption thereof is high in comparison with those of the arithmetic portion, etc., and the indication of the unnecessary zeros is not negligible.

SUMMARY OF THE INVENTION

It is, accordingly, an object of the present invention to provide a zero suppression circuit which can reduce the power consumption in an indicator circuit.

Another object of the present invention is to provide a zero suppression circuit which prevents unnecessary zeros below a decimal point from being indicated.

Still, another object of the present invention is to provide a zero suppression circuit which prevents unnecessary zeros in both the upper and lower places from being indicated.

The present invention itself and further objects of the present invention will become apparent from the following detailed description taken with reference to the accompanying drawings.

BRIEF DESCRIPTION OF THE DRAWINGS

FIG. 1 is a connection diagram showing the zero suppression circuit according to the present invention;

FIG. 2 is a connection diagram showing a digit discriminating circuit which discriminates whether or not a digit from 1 to 9 or a decimal point is present in each place of a decimal number; and

FIG. 3 is a chart showing timing pulses used in the circuits in FIGS. 1 and 2.

PREFERRED EMBODIMENT OF THE INVENTION

FIG. 1 shows an embodiment of the zero suppression circuit according to the present invention.

Referring to the figure, RG₁ designates a register, which is composed of eight flip-flop circuits FF₁–FF₈. The flip-flop circuits FF₁–FF₈ are connected in cascade. Each of these flip-flop circuits is constructed as

a two-phase delay type flip-flop circuit which uses a digit pulse D₀ and a clock pulse ϕ_2 as shift pulses (or trigger pulses). Information is written in accordance with the timing of the clock pulses ϕ_2 .

D₁ denotes a circuit for detecting unnecessary zeros in upper places, which is composed of OR circuits OG₁–OG₈. D₂ indicates a circuit for detecting unnecessary zeros in lower places, which is composed of OR circuits OG₁₁–OG₁₈. The OR circuit OG₁ receives the output signals of the eight flip-flop circuits FF₁–FF₈ as its inputs. The 7-input OR circuit OG₂ receives the output signals of the flip-flop circuits FF₂–FF₈ as its inputs. In this manner, the i-th (i = 1, 2, . . . 8) (9 – i)-input OR circuit OG_i in the unnecessary-upper-zero detector circuit D₁ receives as its inputs the output signals of the flip-flop circuits from that FF_i in the i-th place (as determined from the lowermost place) to that FF₈ in the uppermost place. On the other hand, the i-th (i = 1, 2, . . . 8) i-input OR circuit OG₁₈ in the unnecessary-lower-zero detector circuit D₂ conversely receives as its inputs the output signals of the flip-flop circuits from that FF_i in the i-th place to that FF₁ in the lowermost place.

D₃ represents a circuit for detecting unnecessary zeros in upper and lower places, which is composed of eight 3-input AND circuits AG₁–AG₈. On the input side of the i-th AND circuit AG_i, there are applied output signals of the respective i-th OR circuits OG_i and OG₁₈ of the unnecessary-upper-zero detector circuit D₁ and unnecessary-lower-zero detector circuit D₂. To all the AND circuits AG₁–AG₈, a timing pulse T_H–DT_H is applied as a control input. Although, in order to facilitate the explanation, the 1-input OR circuits OG₈ and OG₁₁ are shown in the detector circuits D₁ and D₂, they are not necessarily required. For example, the flip-flop circuit FF₈ and the AND circuit AG₈ may be directly connected.

RG₂ designates a register, which is composed of two-phase delay type flip-flop circuits FF₁₁–FF₁₈ being the same in construction as the foregoing flip-flop circuits FF₁–FF₈. The flip-flop circuits FF₁₁–FF₁₈ are connected in cascade. The output side of the flip-flop circuit FF₁₁ is fed-back through an AND circuit AG₁₀ onto the input side of the flip-flop circuit FF₁₈. The formation of the feedback loop is controlled by a timing pulse T_L. On the input side of the flip-flop circuit FF₁₁ in the i-th place, an output signal of the i-th AND circuit AG_i is applied.

FIG. 2 shows a digit discriminating circuit to be connected at the stage preceding the zero suppression circuit in FIG. 1. The digit discriminating circuit discriminates whether a decimal point or a digit from 1 to 9 is present or absent in each place of a decimal number.

Referring to the figure, RN indicates a numeral register. Where the binary-coded decimal system is adopted as the notation, a decimal number of one figure is stored by four bits of flip-flop circuits FF₁₀₁–FF₁₀₄. Assuming that the calculating or indicating capability of the calculator concerned is eight places, the register RN requires a number of such flip-flop circuits by at least 8 × 4 bits. Each of the flip-flop circuits FF₁₀₁–FF₁₀₄ is constructed as a two-phase delay type flip-flop circuit whose shift pulses are clock pulses ϕ_1 and ϕ_2 .

FF₁₀ designates a set preference flip-flop circuit. Applied at its set input S is an output signal of the flip-flop circuit FF₁₀₄ at the second bit in the lowermost place of the register RN, while applied at its reset input R is a bit signal BT₄. The flip-flop circuit FF₁₀ is also in the

construction of the delay type in which the shift operation is effected by the clock pulses ϕ_1 and ϕ_2 . The truth table is given below.

S	R	Q_{n+1}
0	0	0
1	0	1
0	1	0
1	1	1

RD represents a decimal-point register, which is used to store the position of the decimal point of the number stored in the numeral register RN and which is composed of eight flip-flop circuits $FF_{21} - FF_{28}$. These flip-flop circuits have the construction of the two-phase delay type flip-flop circuit whose shift pulses are the digit pulse D_p and the clock pulse ϕ_2 .

Output signals of the flip-flop circuit FF_{10} and the decimal-point register RD are combined by an OR circuit OG_{10} . The resultant signal is fed to the register RG_1 .

Various pulse signals for use in the embodiment will now be explained with reference to FIG. 3. In the figure, the upper level of each pulse signal indicates a reference potential or the ground potential (logical 1), while the lower level a negative potential (logical 0). The clock pulses ϕ_1 and ϕ_2 are generated by, for example, astable multivibrators. They are continuously generated within the calculator and are employed for the shifting or triggering operation of the memory elements (delay type flip-flops) connected in cascade in the registers, the other flip-flop circuits, etc. Bit signals $BT_1 - BT_4$ are used where binary parallel signals derived from an encoder are to be transformed into binary series signals. In the embodiment, the bit signal BT_4 is utilized as the reset input signal of the flip-flop circuit FF_{10} . Digit signals $DT_1 - DT_8$ are used as, for example, place switching signals in the dynamic indication system. In the embodiment, they are used as the control pulses of the detector circuit D_p . The digit pulse D_p is used for distinguishing the places of the binary-coded decimal number, while a word pulse W_p (not especially employed in the embodiment) serves to distinguish words. The characteristic equations of the respective pulses are:

$$D_p = BT_4 \cdot \bar{\phi}_1, \quad W_p = BT_4 \cdot \bar{\phi}_1 \cdot DT_8 \cdot T_N$$

Accordingly, the pulses D_p and W_p can be formed of the pulses previously stated. The bit signals $BT_1 - BT_4$ and the digit signals $DT_1 - DT_8$ can be respectively produced from the clock pulses ϕ_2 and the bit signal BT_1 by utilizing counters etc. Here, the pulse width of the bit signals $BT_1 - BT_4$ is equivalent to the period of the clock pulses ϕ_1 or ϕ_2 , and is equivalent to the time of 1 bit of the binary series signal. The pulse width of the digit signals $DT_1 - DT_8$ and the period of the digit pulses D_p are equivalent to the period of the bit signals $BT_1 - BT_4$, namely, the time of one place (4 bits) of the series binary-coded decimal number. The timing pulses T_L and T_N are used for the control of the register and so forth, and have a pulse width equal to the period of the digit signals. In this manner, as the various timing pulses for use in the embodiment, pulses for use in the

other circuits of the electronic calculator can be employed as they are.

The operation of the zero suppression circuit thus constructed will be described in detail hereunder on every block.

1. Register RG_1

The register RG_1 stores a decimal-point signal and a signal representing whether the digits of the respective places are any one of the numbers from 1 to 9 or 0.

For example, where the position of the decimal point is specified at the fifth place as determined from the lowermost place and where a four-figure number 10.34 is set, the former signal is made 0010000, and the latter signal is made 00101100 if the digits 1 to 9 are converted into a logical 1 and the digit 0 is converted into a logical 0. Thus, a signal 00111100 corresponding to the logical sum between both the above signals is fed to and stored in the register RG_1 .

Accordingly, when the output of the flip-flop circuit FF_i in the i -th place becomes 1 in a predetermined period (at $I_H \cdot DT_8 = 1$), it becomes known that either a digit from 1 to 9 or the decimal point exists in the i -th place.

When, conversely, it becomes 0, it becomes known that neither a digit from 1 to 9 nor the decimal point exists in the i -th place, namely, that only the digit 0 exists in the i -th place.

2. Unnecessary - Upper - Zero Detector Circuit D_1

The circuit D_1 for detecting unnecessary zeros in upper places detects whether unnecessary zeros are present in each place and the places above it, in other words, if either a digit from 1 to 9 or a decimal point is present in the places.

In more detail, the i -th OR circuit OG_i receives the output signals of the i -th to eighth flip-flop circuits $FF_i - FF_8$ as its inputs. When any one of the signals becomes 1, it is judged that a digit from 1 to 9 or the decimal point is existent in or above the i -th place and that no unnecessary zero is existent therein. For example, for a number 03005678 or a number 00.005678, the digits of the fifth and sixth place are 0s, but any digits from 1 to 9 or the decimal point is present in a place above the fifth and sixth places. As a result, the outputs of the OR circuits OG_5 and OG_6 become 1. It is, accordingly, judged that no unnecessary zero is existent in the fifth and sixth places.

On the other hand, when all the output signals of the i -th to eighth flip-flop circuits $FF_i - FF_8$ becomes 0, the output of the OR circuit OG_i becomes 0. It is, accordingly, judged that neither a digit from 1 to 9 nor the decimal point exists in and above the i -th place, and that the digit 0 in the i -th place is unnecessary.

3. Unnecessary-Lower-Zero Detector Circuit D_2

The circuit D_2 for detecting unnecessary zeros in lower places detects whether unnecessary zeros are present in each place and the places below it, in other words, if either a digit from 1 to 9 or a decimal point is present in the places.

In more detail, the i -th OR circuit OG_{11} receives the output signals of the first to i -th places of flip-flop circuits $FF_1 - FF_i$ as its inputs. When any one of the signals becomes 1, it is judged that a digit from 1 to 9 or the decimal point is existent in or below the i -th place, and that no unnecessary zero is existent therein.

On the other hand, when all the output signals of the flip-flop circuits $FF_1 - FF_i$ become 0, the output of the OR circuit OG_{11} becomes 0. It is, accordingly, judged that neither a digit from 1 to 9 nor the decimal point ex-

ists in and below the i -th place, and that the digit 0 in the i -th place is unnecessary.

4. Unnecessary-Upper-and-Lower-Zero Detector Circuit D_3

On the basis of the detecting results of the unnecessary-upper-zero detector circuit D_1 and the unnecessary-lower-zero detector circuit D_2 , the detector circuit D_3 detects whether unnecessary zeros are present in both upper and lower places. In other words, the detector circuit D_3 detects if a digit from 1 to 9 or the decimal point is present in each place and places above and below it. In case where a digit from 1 to 9 or the decimal point is present in both the upper and lower places, it is judged that the digit in the particular place is to be indicated.

The i -th AND circuit AG_i receives as its inputs the output signal of the OR circuit OG_i for detecting the presence of unnecessary zeros in an above the i -th places and the output signal of the OR circuit OG_{ii} for detecting the presence of unnecessary zeros in and below the i -th places. Therefore, where at least one of the received output signals is 0, it becomes known that the unnecessary zero exists in the i -th place.

For example, where the position of the decimal point is specified at the fifth place as determined from the lowermost place and where a four-figure number 10.04 is set (0010.0400), the contents of the register RG_1 become 00110100, and the output of the detector circuit D_3 becomes a signal 00111100 which corresponds to the logical product between the output 00111111 of the unnecessary-upper-zero detector circuit D_1 and the output 11111100 of the unnecessary-lower-zero detector circuit D_2 . It is thus detected that the unnecessary zeros exist in the upper two places and the lower two places.

The timing pulse $T_H - DT_3$ impressed on each AND circuit of the detector circuit D_3 is utilized as the signal for control. More specifically, when the decimal point signal and the signal indicative of the existence or non-existence of a digit from 1 to 9 in each place are loaded in the register RG_1 (when both the timing pulse T_H and the digit signal DT_3 become 1), the gate of each AND circuit is opened, and the detecting result is fed to the succeeding circuit.

In this way, on the output side of the detector circuit D_3 , whether or not the unnecessary zeros are present in the respective places appears in the form of parallel binary signals. In the static indication system, they can be used as indication control signals (zero suppress signals) without any further processing. In the dynamic indication system, only the necessary indication can be effected in such way that the parallel binary zero suppress signals are transformed into series signals by means of the register RG_2 as will now be described, and that the transformed signals are fed into an indication control circuit.

5. Register RG_2

The register RG_2 stores in series the detecting results of the detector circuit D_3 . The rear stage portion of the register RG_2 is fed-back to the front stage portion by the AND circuit AG_{10} . The opening and closure of the feedback loop is controlled by the timing pulse T_L .

In the period in which the timing pulse $T_H - DT_3$ is 1, the detected results of the unnecessary zeros in the respective places are simultaneously written into the flip-flop circuits $FF_{11} - FF_{10}$. Next, when the timing pulse T_L becomes 1, the detected results are circulatively stored

within the register RG_2 . Subsequently, when the timing pulse T_L becomes 0, the feedback loop of the register RG_2 is opened, and the contents of the register RG_2 are reset. Then, rewriting of the detecting results becomes possible.

The register RG_2 serves also as a register for arithmetic control, for example, a register for grasping the degree of progress of calculations in multiplication and division. In this case, inputs may be fed through the front stage portion of the register RG_2 with the gates of the AND circuits $AG_1 - AG_8$ kept closed during the calculations.

As described above, in accordance with the embodiment, the unnecessary zeros in the upper and lower

places can be prevented from being indicated. For example, in the case previously mentioned (the case of indicating 0010.0400), the unnecessary 0s in the upper two places and the lower two places are extinguished, and only the digits in the necessary places are displayed as 10.04. Accordingly, the power consumption in the indicating portion diminishes, and the indication becomes easy to read. This applies not only to the case where the indication is conducted with luminescent elements, but also to a case where the display is performed with an electronic typewriter.

Lastly, description will be made of the operation of the circuit which generates the signals to be delivered to the register RG_1 , that is, the digit discriminating circuit which discriminates whether or not a decimal point or a digit from 1 to 9 exists in each place.

6. Digit Discriminating Circuit

Where any number is set or where a calculated result is requested, the number is stored in the form of binary-coded decimal signals in a manner to be circulated in the numeral register RN . Similarly, the decimal point signal representative of the position of the decimal point of the number is circulatively stored in the decimal point register RD .

For example, where the position of the decimal point is specified at the fifth place as determined from the lowermost place and where the four-figure number 10.34 is set, the contents of the numeral register RN become 00103400 (from the uppermost place to the lowermost one) when $T_H - DT_3 - BT_4 - \phi_2$ becomes 1. At this time, the contents of the decimal point register RD become 00010000 (from the uppermost place to the lowermost place).

The number thus stored in the numeral register RN is fed from the flip-flop circuit FF_{101} at the second bit to the set preference flip-flop circuit FF_{10} and serially at every bit. In the flip-flop circuit FF_{10} , it is discriminated whether the digit in each place is any one of the digits 1 to 9 or zero. In more detail, the flip-flop circuit FF_{10} judges if there is a 1 in the series binary signal of four bits within one place of the binary-coded decimal number. For example, where a series binary signal 0010 representative of a decimal number 4 is fed, the flip-flop circuit FF_{10} is set by the signal 1 at the second bit, and thereafter maintains the set state until it is reset by the bit signal BT_4 . Accordingly, a series binary signal 1110 appears on the output side of the flip-flop circuit FF_{10} . Since the bit signal BT_4 is utilized as the reset signal, the state of the flip-flop circuit FF_{10} for a certain place exerts no influence on the state for the succeeding place.

As stated above, if the contents 1 exist at any bit of a determined place of a binary-coded decimal number,

the state of the flip-flop FF_{10} is thereafter forced into 1 irrespective of the presence or absence of 1 or 0 within the same place. For example, where the number to be indicated is 0000 0100 0010, the outputs of the flip-flop FF_1 become 0000 1100 1110. Therefore, the 5 detection of every fourth bit of the outputs of the flip-flop FF_{10} makes it possible to discriminate if there is 1 within one place (4 bits) of the binary-coded decimal number. That is, the detection makes it possible to judge if the digit of the place is the decimal zero. Accordingly, the flip-flop circuit FF_{10} discriminates between the presence and absence of the digit 0 (or any digit from 1 to 9) at every place, and delivers the result to the OR circuit OG_{10} in the form of the signal 0 or 1. Consequently, for example, when binary signals of 15 eight places and 32 bits as correspond to a decimal number 00103400 are supplied from the register RN, the flip-flop circuit FF_{10} generates signals in which the contents of every fourth bit of the respective places are 00101100.

On the other hand, where the decimal point is located at, for example, the fifth place as determined from the lowermost place, the decimal point register RD feeds a decimal point signal 00010000 to the OR circuit OG_{10} . The decimal point signal at this time is 25 equivalent to the digit signal DT_5 .

Accordingly, a signal corresponding to the logical sum between the decimal point signal and the signal representative of whether the digit of each place is any one of the digits 1 to 9 or 0 appears on the output side of the OR circuit OG_{10} . For example, where the position of a decimal point is specified at the fifth place and where a four-figure number 10.34 is set, the outputs of the OR circuit OG_{10} for every fourth fit of the respective places become 00111100 which is the logical sum 35 between 00101100 and 00010000.

Even when a 4-input OR circuit is prepared in lieu of the flip-flop circuit FF_{10} and has output signals of the flip-flop circuits FF_{101} - FF_{108} applied as its inputs, it 40 can be similarly discriminated whether or not the binary-coded signal 1 is contained in each decimal place (in 4 bits).

While We have shown and described several embodiments in accordance with the present invention, it is understood that the same is not limited thereto but is susceptible of numerous changes and modifications as known to a person skilled in the art, and We therefore do not wish to be limited to the details shown and described herein but intend to cover all such changes and modifications as are obvious to one of ordinary skill in the art. 50

What we claim is:

1. A zero suppression circuit comprising:
first means, responsive to an input signal representative of an n -digit decimal number, and having an n 55 element memory capacity, for storing therein respective signals representative of whether a digit of said decimal number is the digit zero, and including means for storing, in one of said elements, a signal representative of the position of a decimal point in said decimal number; and
second means, responsive to the contents of said first means, for detecting the presence of the digit zero at those digit positions of said n digit decimal number which are unnecessary for completely representing said decimal number and comprising a first detector circuit including n gate circuits respec-

tively coupled to the n memory elements of said first means, so that the outputs of the first to i -th memory elements of said first means are coupled to the i -th gate circuit of said first detector circuit, wherein $1 \leq i \leq n$.

2. A circuit according to claim 1, wherein said second means comprises a second detector circuit including n gate circuits respectively coupled to the n memory elements of said first means, so that the outputs of the n th to i th memory elements of said first means are coupled to the i -th gate circuit of said second detector circuit, where $1 \leq i \leq n$.

3. A circuit according to claim 2, wherein said second means further includes a third detector circuit, responsive to the outputs of said first and second detector circuits, for logically combining the respective outputs of the gate circuits thereof, and for providing an output signal representative of the presence of zeros at digit positions which are unnecessary for completely representing said decimal number.

4. A circuit according to claim 3, further including an output register, coupled to said third detector circuit for storing the output signals therefrom in n memory element positions.

5. A circuit according to claim 3, wherein said first means includes

a numeral register, having n storage positions, for receiving a signal representative of a decimal number and converting said received number into an n digit decimal number,
a decimal point register having n storage positions, for storing the position of a decimal point in said decimal number, and
means for logically combining the contents of selected ones of the storage positions of said numeral and decimal point registers for providing an n bit signal representative of those digit positions of said n digit decimal number which are digits other than zero and the position in said n digit decimal number at which a decimal point occurs.

6. A circuit according to claim 5, further including an output register, coupled to said third detector circuit for storing the output signals therefrom in n memory element positions.

7. A zero suppression circuit comprising:
first means, responsive to an input signal representative of an n digit decimal number, and having an n element memory capacity, for storing therein respective signals representative of whether a digit of said decimal number is the digit zero and including means for storing, in one of said elements, a signal representative of the position of a decimal point in said decimal number, said first means further including

a numeral register, having n storage positions, for receiving a signal representative of a decimal number and converting said received number into an n digit decimal number,
a decimal point register having n storage positions, for storing the position of a decimal point in said decimal number, and
means for logically combining the contents of selected ones of the storage positions of said numeral and decimal point registers for providing an n bit signal representative of those digit positions of said n digit decimal number which are digits other than

zero and the position in said n digit decimal number at which a decimal point occurs; and second means, responsive to the contents of said first means, for detecting the presence of said digit zero at those digit positions of said n digit decimal number which are unnecessary for completely representing said decimal number.

8. A circuit according to claim 7, wherein the logically combining means of said first means comprises means for logically combining the contents of the next to least significant storage position of said numeral register with the least significant storage position of said decimal point register.
